UNITED STATES PATENT OFFICE.

JOHN J. HEALY, OF FAR ROCKAWAY, NEW YORK.

DESIGN FOR A BOTTLE.

SPECIFICATION forming part of Design No. 19,577, dated January 14, 1890.

Application filed November 23, 1889. Serial No. 331,387. Term of patent 14 years.

To all whom it may concern:

Be it known that I, JOHN J. HEALY, a citizen of the United States, residing at Far Rockaway, in the county of Queens and State of New York, have invented and produced a new and original Design for Bottles, of which the following is a specification, reference being had to the accompanying drawing, forming a part thereof, and which represents a perspective view of my design.

The design consists of the figure A, the

outlines *a* of which resemble somewhat a trefoil or shamrock-leaf, and a series of lines *b*, drawn upon the figure in imitation of the veins of a leaf.
